United States Patent Office

Des. 227,405
Patented June 19, 1973

227,405

PAIR OF SPECTACLES

Anthony Shindler, Brookline, Mass., assignor to American Optical Corporation, Southbridge, Mass.

Filed Aug. 27, 1970, Ser. No. 24,737

Term of patent 14 years

Int. Cl. D16—06

U.S. Cl. D57—1 F

FIG. 1.

FIG. 2.

FIG. 3.

FIG. 4.

FIG. 1 is a perspective view of the pair of spectacles showing my new design;

FIG. 2 is a side elevational view thereof;

FIG. 3 is a front elevational view thereof on a reduced scale;

FIG. 4 is a top plan view thereof on a reduced scale.

I claim:

The ornamental design for a pair of spectacles, as shown and described.
